M. WESNER.

PROJECTILE.

APPLICATION FILED SEPT. 17, 1915.

1,169,704.

Patented Jan. 25, 1916

UNITED STATES PATENT OFFICE.

MARTIN WESNER, OF CLEVELAND, OHIO.

PROJECTILE.

1,169,704.

Specification of Letters Patent. Patented Jan. 25, 1916.

Application filed September 17, 1915. Serial No. 51,162.

To all whom it may concern:

Be it known that J. MARTIN WESNER, a citizen of the United States, residing at 2698 East Sixty-second street, in the city of Cleveland, county of Cuyahoga, and State of Ohio, have invented a new and useful Improvement in Projectiles, of which the following is a specification; the principle of the invention being herein explained and the best mode in which I have contemplated applying that principle, so as to distinguish it from other inventions.

My invention pertains to a projectile and more particularly to the configuration of the point thereof.

The object is the provision of a structure of this character which will effect greater penetration and incidentally increased velocity.

I have discovered that the rotary movement of a projectile which is imparted by the rifling could be utilized effectively to initiate a drilling entry at the moment of impact. Accordingly the end of the nose of a projectile embodying my invention is fashioned as a drill.

I have carried on experiments during a period of over a year using 22 short cartridges. I discovered; That the ordinary leaden bullet of the cartridge stated penetrated about one-half an inch through the particular piece of hard wood which I first selected as a target, whereas the same cartridge supplied with a special Spitzer (steel nosed) type of bullet penetrated the same piece of wood at the same range to a distance of about three-fourths of an inch; and that the same cartridge supplied with a steel drill fixed in the nose thereof penetrated the same piece of hard wood at the same range to an extent of one and one-eighth inches. That the same three different types of bullets fired from the same cartridge over the same range directly against the head of an ordinary hatchet (malleable iron) produced the following results respectively: The impact of the leaden bullet produced no results whatever to the naked eye, whereas the Spitzer type of bullet made a very slight nick there-in; and my inventive drill type of bullet not only cut into the metal but actually stuck in the same and was covered by a mass of flattened lead. That upon firing the same three different types of bullets against a thin sheet of steel across the same range the following in respective order was no-

ticed. The impact of the leaden bullet caused no surface abrasion whatever, whereas the Spitzer type of bullet made an insignificant nick; and my inventive type of bullet drilled its way entirely through such sheet of steel.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

Adverting to the drawings: Figure I is a side elevation of a complete cartridge in which is fitted a bullet embodying my invention. Fig. II is an enlarged and front perspective of the bullet or projectile removed from the cartridge. Fig. III is a part section and part side elevation of Fig. II showing the detachable connection between the body of the projectile and the drill. Fig. IV is an end view of Fig. II. Fig. V is a side view partly sectioned of a modification of my invention. Fig. VI is a section on line VI—VI of Fig. V looking in the direction indicated by the arrows. Fig. VII is a side view partly sectioned of a second modification of my invention. Fig. VIII is an end view of Fig. VII. Fig. IX is a side view of a third modification. Fig. X is an end view of Fig. IX.

It should be understood that the experiments which have been made appear to justify the assumption that the caliber of the projectile is a matter of no moment and that the increased effectiveness of a projectile embodying my invention while it may vary according to its size, weight and velocity should be measurable in every instance. The preferred form shown in its entirety in Fig. I illustrates a small arm cartridge having the main shell 1 with a reduced end 2 in which the body 3 of the projectile is fitted. The forward end of the body is preferably somewhat tapered at 4, for a purpose that will be presently explained. The nose of the projectile proper is fashioned with a screw threaded opening 5 in which the complementarily threaded and reduced shank 6 of a drill 7 is detachably seated. The said connection should be

presumed as the reverse of the direction of rotation to be imparted by the rifling of the gun. Figs. II and III illustrate a drill of slightly less diameter than the body 3 of the projectile but such that the tapering portion 4 of the latter merges therewith. My preferred type of drill is seen to be of the double flute type with a point formed by an elongated taper 8. I prefer also to have the outer portions of the two cutting edges 9 of the drill point backwardly curved with reference to or in opposition to the direction of advance of the nearest flute as appears in Fig. IV. This conformation affords an added clearness and has produced better results. The purpose in having the body of the projectile slightly larger than the diameter of the drill is in order to protect the rifling of the gun from the ultra-hardened metal of which the drill is composed. It is not necessary that the body 3 of the projectile be quite as hard as the drill. A close inspection of Fig. II discloses that one of the flutes of the drill extends a certain distance rearwardly along the body of the projectile at 10 in order to enable a breech end portion of one of the lands of the rifling to occupy it. Thence such land portion begins to take hold of and impart grooves around the somewhat softer portions of the periphery of the body 3 just where such flute ends and therefore carry out as nearly as possible a harmonious cycle of rotation. In order to make this the more possible the cartridge should be inserted in the breech of the gun in a certain way such that the land of the rifling nearest the breech will take hold or bite upon the projectile substantially in continuation of the spiral direction of the groove.

The modification disclosed by Figs. V and VI comprises a projectile 11 having a similarly slightly tapering nose 12 in which is fashioned centrally a square hole 13 for the reception of a similarly squared shank 14 of a drill 15 tapered throughout its length. I have discovered this type of drill to be equally effective when an object is struck at an angle.

Figs. VII and VIII relate to a projectile 16 having again a slightly tapered portion

17 on which a drill 18 is an integral though hardened part. Such drill is furthermore provided with a more stubby point 19 and has four instead of two flutes one of which 55 may or may not extend a given distance into the body 16.

Figs. XI and X relate to a large and heavier type of projectile wherein the body 21 of the projectile itself has a tapering nose 60 22 of predetermined curvature which nose is itself fluted at 23 to provide cutting edges 24 and one of which flutes extends rearwardly at 25 into the front portion of the body 21 for similar reasons as have been 65 earlier given.

I claim:

1. A projectile having a tapering nose with a peripheral portion of relatively softer material, said nose furthermore carrying at 70 its extremity a drill of relatively harder material and forming a smooth continuation of said tapering nose, said peripheral portion being fashioned with a groove forming a continuation of the cycle of one of the 75 grooves of said drill.

2. A projectile including a main body portion and a nose of lesser diameter in the form of a drill, a flute of the latter being extended into such body portion whereby to 80 be adapted to be put in relative engagement with the land of the rifling.

3. A projectile comprising a body portion having a tapered nose provided centrally with a hole, and a drill of relatively smaller 85 circumference separately fitted in said hole and merging with the end of said nose, said body being fashioned with a narrow groove forming a continuation of one flute in said drill whereby the rotation imparted by the 90 rifling is initiated along said groove.

4. A projectile having a body portion adapted to take to the rifling of the gun barrel, and a drill carried by said body portion, said body portion being fashioned with 95 a groove of like twist as and merging with a flute in said drill whereby the rifling impression imparts rotation to said body portion in lineal cycle with said flute.

Signed by me, this 13th day of September, 100
1915.

MARTIN WESNER
